US00D732101S

(12) **United States Design Patent**
Hasuda

(10) **Patent No.:** **US D732,101 S**
(45) **Date of Patent:** **** Jun. 16, 2015**

(54) **CAMERA LENS**

(71) Applicant: **Nikon Corporation**, Tokyo (JP)

(72) Inventor: **Masanori Hasuda**, Fujisawa (JP)

(73) Assignee: **Nikon Corporation**, Tokyo (JP)

(**) Term: **14 Years**

(21) Appl. No.: **29/451,777**

(22) Filed: **Apr. 8, 2013**

FIG. 1 is a perspective view of an embodiment of a camera lens showing my new design;
FIG. 2 is a rear elevational view thereof;
FIG. 3 is a top plan view thereof;
FIG. 4 is a bottom plan view thereof;
FIG. 5 is a right side elevational view thereof; and,
FIG. 6 is a left side elevational view thereof.
The features shown in broken lines in the drawings depict environmental subject matter only and form no part of the claimed design. The dot-dashed lines denote the boundary of the claim and form no part of the claimed design.

1 Claim, 6 Drawing Sheets
